UNITED STATES PATENT OFFICE.

WILLIAM E. SHELDON, JR., OF MEDFORD, MASSACHUSETTS.

CABINET-MAKER'S CLAMP.

SPECIFICATION forming part of Letters Patent No. 295,589, dated March 25, 1884.

Application filed August 2, 1883. (No model.)

To all whom it may concern:

Be it known that I, WILLIAM E. SHELDON, Jr., of Medford, in the county of Middlesex and State of Massachusetts, have invented 5 new and useful Improvements in Cabinet-Makers' Clamps, of which the following is a specification.

This clamp is intended as an improvement over that now generally in use in cabinet-makers' shops for holding tightly together glued pieces, &c.

In the accompanying drawings, in which similar letters of reference indicate like parts, Figure 1 is a view in perspective of my improved clamp. Fig. 2 is a longitudinal vertical section of the same. Figs. 3 and 4 are cross vertical sections on lines *x* and *y*, respectively, Fig. 1.

A represents the bar, provided, as usual, 20 with the transverse grooves *a*.

B is the head-block, provided, as usual, with the screw *C*. To this head-block are secured side plates, *D*, provided with slides *d*, fitting vertically into the slots *e* in the frame *E*. This 25 frame is fitted onto the bar *A* by means of the shoes *f*, and secured to it by the rivet *g*. By means of this construction the head-block may be readily adjusted vertically the length of the slots *e* less the length of the slides *d*. The 30 cross-bar *G* prevents the head-block from slipping out in case the slots extend to the upper end of the frame, and strengthens the latter. In order to provide sufficient friction to hold the head-block in any desired position, springs

H are placed between the plates *D* and frame 35 *E*, secured to the former. (See Fig. 4.)

I is the tail-block, provided with the usual swinging bar or catch, *J*, adapted to hold the tail-block in any desired position against the pressure of the screw by catching in one of 40 the grooves *a*. In order to hold the lower or horizontal portion of the bar *J* up against the lower side of the bar *A*, so that it will be sure to catch in a groove, *a*, I provide the spring *K*, of the shape shown, extending from beneath the bar *A* upward on each side, coiling around the pin *L*, and bending downward and forward at *K'*, and being secured at its ends to opposite sides of the swinging bar *J*, below its point of connection with the tail-block, so 45 as to obtain a good leverage. A slide, *P*, is loosely secured to the spring *K* below the bar *A*, so that the spring cannot catch in the grooves *a*. Thus the action of the catch *J* is rendered positive. 55

Having thus fully described my invention, what I claim, and desire to secure by Letters Patent, is—

In a cabinet-maker's clamp, the combination of the head-block, provided with the slide 60 *d*, and suitable spring, *H*, and the frame *E*, provided with the slot *e*, substantially as and for the purpose set forth.

WILLIAM E. SHELDON, JR.
